UNITED STATES PATENT OFFICE.

LOUIS SCHULTZ, OF NEW YORK, N. Y.

DESIGN FOR QUILTING.

SPECIFICATION forming part of Design No. 14,147, dated July 31, 1883.

Application filed March 5, 1883. Term of patent 7 years.

To all whom it may concern:

Be it known that I, LOUIS SCHULTZ, of New York, in the county and State of New York, have invented a new and original Design for 5 Quilting, of which the following is a specification.

The invention consists in a pattern for the stitching performed in quilting fabrics.

The accompanying drawing is a face view of 10 a portion of a fabric quilted in accordance with this invention.

A designates rows of square or diamond-shaped figures, and B designates rows of zigzag figures. Both kinds of figures are delineated by stitching. In a large fabric there are alternate rows of the two kinds of figures. The square or diamond-shaped figures A have 15 their corners in contact, and consequently their opposite sides are in continuous lines, as clearly shown. The zigzag figures B are composed of straight portions, which are parallel

with the adjacent sides of the square or diamond-shaped figures, and have their angles opposite the adjacent angles of the square or diamond-shaped figures.

What I claim as my design, and desire to secure by Letters Patent, is—

The pattern for quilting, consisting of rows or groups of square or diamond-shaped figures having their corners in contact, and consequently their opposite sides in continuous lines, and alternate rows or groups of zigzag figures composed of straight portions which are parallel with adjacent sides of the groups of square or diamond-shaped figures, and have 30 their angles opposite adjacent angles of the groups of square or diamond-shaped figures, substantially as described and shown.

LOUIS SCHULTZ.
